UNITED STATES PATENT OFFICE.

EDWARD E. BARRETT, OF LA GRANGE, ILLINOIS.

COAL-HANDLING DEVICE.

No. 870,609.

Specification of Letters Patent.

Patented Nov. 12, 1907.

Application filed January 12, 1907. Serial No. 352,049.

To all whom it may concern:

Be it known that I, EDWARD E. BARRETT, a citizen of the United States, residing at La Grange, in the county of Cook and State of Illinois, have invented a 5 certain new and useful Improvement in Coal-Handling Devices, of which the following is a specification.

My invention relates to conveying apparatus and particularly to apparatus for hoisting material and distributing it over a considerable area, and has for 10 its object to provide new and improved arrangements and devices whereby the processes of hoisting and distributing may be carried on simultaneously.

The invention is illustrated in the accompanying drawings, wherein

15 Figure 1 is a vertical sectional view through the elevator shaft, and Fig. 2, a vertical sectional view on line 2-2 of Fig. 1.

Like letters of reference indicate like parts in all the drawings.

20 The invention is shown and will be described as embodied in a coal handling plant suitable for use on railroads where the coal is unloaded from cars, conveyed to buckets or bins and there held in readiness to be unloaded into the engine tenders. This is, 25 however, merely an illustrative application of the invention which might be embodied in a very different sort of conveying and storage plant and utilized for a wholly different purpose than that above indicated. The drawings are, therefore, to be taken as in a sense 30 diagrammatic.

In the drawings, A A represent tracks upon which the loaded coal cars are received. Beneath these tracks are the bins A¹ A¹ with inclined floors A² A² and feed openings A³ A³ controlled by the gates A⁴ A⁴ 35 hinged to a stationary part of the structure as shown.

B represents the structure for the elevators, which are shown as a number of buckets working in pairs so that one of each pair will be in position to load at the bottom of the shaft while the other is dumping 40 its contents at the top of the shaft. For example I have shown four of these buckets. I shall describe particularly the pair of buckets operating upon the left hand side of the elevator shaft as it is shown in Fig. 1, it being understood that the arrangement on 45 the other side of the shaft may be in all respects similar. These buckets are designated by the letters C, C¹. I have shown the buckets as self dumping buckets having one side C² pivoted to the body of the bucket and held closed by a latch C³ pressed by a spring C⁴. The 50 latch has the tripping arm C⁵ which comes in contact with a tripper C⁶ freeing the part C² which forms a chute for the coal, as is shown in the upper part of Fig. 2. The buckets, it will be understood, are suitably guided in the structure B.

D D¹ are cables attached to the drum E and extending over sheaves F, F¹. To the ends of these cables are attached the buckets C, C¹. The cables are secured to the drum so that one unwinds while the other winds and are guided on the idlers G, G¹.

H represents bins or pockets covered by the shed H¹. In the arrangement shown the bins are on each side of the elevator structure B. They may be provided with suitable gates and chutes H² extending over the coaling tracks J J in any desired and well known manner. Over the bins H at one side of the 65 elevator structure is a track K preferably inclined and on this track runs a car K¹ propelled by means of a cable or the like K² extending around an idler K³ and over a drum K⁴ around an idler K⁵ to another car K⁶ running upon a track K⁷ extending over the bins H at the other side of the elevators. A cable K⁸ is attached at one end to the car K¹ and at the other end to the car K⁶ and runs over sheaves K⁹, K¹⁰ and over the rollers K¹¹. The drum K⁴ is arranged on a shaft K¹² turning in bearings K¹³ K¹³. This shaft also carries the sheave F. To insure the closing of the descending buckets I provide a spring K¹⁴ which may be fixed to some stationary part of the elevator structure.

It will be understood that any desired form of elevating means might be used, the particular style of dumping bucket shown being given simply for purposes of illustration.

The cars K¹, K⁶ are arranged to correspond with the arrangements of the buckets C, C¹. When the bucket C is loading at the bottom of the elevator shaft the car K¹ is at the outer end of its track, while the bucket C¹ will, of course, be at the upper end of the elevator shaft and the car K⁶ drawn up beneath it to receive its load. The cars K¹, K⁶ may be of any desired type. For example, they may be automatic dumping cars and trips can be arranged along the tracks K, K⁷ so as to cause the cars to be automatically dumped at the places desired. The tracks K, K⁷ are preferably slanted away from the elevators so that the loaded car will aid in pulling the empty car back to the elevator. The cars K¹, K⁶ in this connection may be very properly called distributing cars as they make it possible to distribute the material handled over a very considerable area. The tracks may, of course, run at any angle or in any direction from the elevator. In this way the breaking of the coal is obviated and its distribution effected by the use of very simple apparatus and of such a character as is little likely to get out of order or broken. It will be understood that the same arrangement of elevator conveyors and distributing cars may be installed on the other side of the plant, that is on the right hand side as shown in Fig. 1.

I wish it to be understood that I do not desire to be limited to the exact details of construction shown and described for obvious modifications will occur to any person skilled in the art. I have shown hinged gates 5 used in connection with the bins A¹, but it will be understood that any other form of gate could be used. The distributing cars are shown as running directly over the bins or receptacles for the material handled, but it will be understood that they only need to be effectively above the same; that is, the cars so arranged as 10 to be capable of discharging into the bins or receptacles. By the use of the word "over" I intend to express broadly such relationship.

The use and operation of my apparatus are as follows: 15 The coal comes in on tracks A, is shoveled or dumped into the bins A¹ and loaded into the buckets through the feed gates A³, A⁴. The bucket when loaded is drawn up to the top of the elevator shaft and, when the bucket is of the type shown, automatically dumps its 20 load into one of the cars K¹ or K⁶ which has been drawn up into position to receive the load by the travel of the cable around the drum K⁴. It will be understood that in the form of apparatus shown the cable will be given two or three turns around the drum in order to prevent 25 slipping. The bucket is then lowered and at the same time the car runs down the track to the place where its load is to be dumped. The car is preferably an automatically dumping car and a tripper may be set at any point in the track to cause the same to dump its load. 30 This tripper has not been shown as the car and its method of dumping forms no part of this invention. The car will continue its travel to the end of the track and then be returned to receive another load from the bucket. As one bucket descends the other, on the 35 other side of the elevator shaft, rises, the cars K¹, K⁶ also working in this alternate order. In this manner coal or such like material may be handled very economically and distributed evenly over a wide area if desired.

40 I claim:

1. In a conveying system, the combination of elevator apparatus comprising a pair of buckets, means for raising and lowering the buckets simultaneously and in alternation, a receptacle to receive the material hoisted by the 45 elevator apparatus, distributing cars operating over the receptacle and into which the material hoisted is loaded, and means for operating the elevator apparatus and distributing cars so that the same operate in conjunction with each other to hoist and distribute the material by a single continuous process.
2. In a conveying system, the combination of elevator apparatus working intermittently in opposite directions to hoist the material with distributing apparatus receiving the material from the elevator apparatus and working intermittently in opposite directions to distribute the material laterally with respect to the elevator apparatus.
3. In a conveying system, the combination of elevator apparatus working intermittently in opposite directions to hoist the material, with distributing apparatus operated 55 by said elevator apparatus receiving the material from the elevator apparatus and working intermittently in opposite directions to distribute the material laterally with respect to the elevator apparatus.
4. In a conveying system, the combination of elevator apparatus, with distributing apparatus operated by said elevator apparatus receiving the material from the elevator apparatus and working intermittently in opposite directions to distribute the material laterally with respect to the elevator apparatus.
5. In a conveying system, the combination of an ele- 60

vator shaft with a pair of elevator buckets, means for alternately raising and lowering the same, a storage receptacle for the material handled, a pair of tracks extending over said storage receptacle from the elevator shaft, a pair of distributing cars, and means for moving said cars in alternation to and from the elevator shaft so that their movements correspond with the movements of the elevator buckets.

6. In a conveying system, the combination of an elevator shaft with a pair of elevator buckets, a single drum, cables attached to said drum whereby said elevator buckets are alternately raised and lowered, a storage receptacle for the material handled, a pair of tracks extending over said storage receptacle from the elevator shaft, a pair of distributing cars, and means for moving said cars in alternation to and from the elevator shaft so that their movements correspond with the movements of the elevator buckets.

7. In a conveying system, the combination of an elevator shaft with a pair of elevator buckets, a single drum, cables attached to said drum whereby said elevator buckets are alternately raised and lowered, a storage receptacle for the material handled, a pair of tracks extending over said storage receptacle from the elevator shaft, a pair of distributing cars, and means operated by the driving mechanism of the elevator buckets for moving said cars in alternation to and from the elevator shaft so that their movements correspond with the movements of the elevator buckets.

8. In a conveying system, the combination of an elevator shaft with a pair of elevator buckets, a common driving device for the elevator buckets, a storage receptacle for the material handled, tracks extending over said receptacle from the elevator shaft, a drum, and cables to operate said cars in alternation to and from the elevator shaft, said drum being associated with the driving mechanism of the elevating buckets.

9. In a conveying system, the combination of elevator apparatus with a storage receptacle for the material handled, a pair of inclined tracks extending from the elevator apparatus over the storage receptacle, cars to run on said tracks, and a common driving device whereby the cars are moved simultaneously and in alternation to and from the elevator device.

10. In a conveying system, the combination of elevator apparatus with a storage receptacle for the material handled, a pair of inclined tracks extending from the elevator apparatus over the storage receptacle, cars to run on said tracks, and a common driving device whereby the cars are moved simultaneously and in alternation to and from the elevator device, said tracks being inclined downward from the elevator device.

11. In a conveyer system, the combination of an elevator bucket adapted to raise the material from a lower level to a higher level, with a car laterally movable in approximately said higher level and adapted to receive the material from the bucket and convey it laterally to distribute it, and means for simultaneously moving the elevator bucket and the car, the latter adapted to travel the entire length of its excursion at each operation and both timed so that they simultaneously reach the point of intersection of their paths.

12. In a conveyer system the combination of an elevator bucket adapted to raise the material from a lower level to a higher level, with a car laterally movable on approximately said higher level and adapted to receive the material from the bucket and convey it laterally to distribute it, the car adapted to travel the entire length of its excursion at each operation, and both car and bucket timed so that they simultaneously reach the point of intersection of their paths.

13. In a conveyer system, the combination of an elevator bucket adapted to raise the material from a lower level to a higher level, with a pair of cars laterally movable on approximately said higher level and adapted to receive material, at least one of them, from said bucket and both at approximately the same point and convey it laterally to distribute it, rails on which said cars travel outwardly and downwardly inclined from the point where they receive their loads, a cable connecting the two cars so

that they are alternately at the outer and inner ends of their excursion, and controlling mechanism associated with such cable.

14. In a conveyer system, the combination of two elevator buckets adapted to raise the material from a lower level to a higher level, a cable which connects them, driving mechanism whereby they balance each other and are alternately at opposite ends of their excursion, with two cars laterally movable on approximately said higher level 10 and adapted to receive the material from the bucket and

convey it laterally to distribute it, rails outwardly inclined from the intersection of the path of the car and bucket and on which the cars travel, a cable which connects the cars, and means for controlling them, said cars alternately at opposite ends of their respective excursions.

EDWARD E. BARRETT.
